UNITED STATES PATENT OFFICE

HENRY B. GREENWOOD, OF GLENARM, MARYLAND, ASSIGNOR TO F. X. HOOPER COMPANY, INC., OF GLENARM, MARYLAND, A CORPORATION OF MARYLAND

FOUNTAIN ROLL FEEDING MEANS FOR PRINTING PRESSES

Application filed December 27, 1929. Serial No. 416,896.

This invention relates to means for operating the fountain rolls of printing presses, and particularly to means whereby the feeding movements of the fountain roll may be varied through a wide range of adjustments. By means of the present improvements these adjustments can be made quickly and while the press is in motion.

In carrying out the invention, I provide a 10 rocking frame which is pivoted on the press frame below the fountain roll and this rocking frame is oscillated in unison with the movements of the printing cylinder. A threaded adjusting bar is journaled in the 15 rocking frame and projects laterally from the pivotal axis of the latter frame. A traveling nut is threaded on to the bar and a link connects this nut with the driving member of an intermittent grip device which is mounted on 20 the fountain roll shaft. By turning the threaded bar, the nut may be adjusted toward or from the pivoted end of the rocking frame, while the press is in motion, to shorten or lengthen the throw of the link and the 25 movement of the driving member of the intermittent grip device. The latter device is of the type in which the parts frictionally engage one another, and hence, any forward movement of the driving member, however 30 slight, will cause a corresponding movement of the driven member.

In the accompanying drawing, which illustrates the invention,

Fig. 1 is a side elevation of part of a printing press, showing the mechanism for operating the fountain roll;

Fig. 2 is a section on the line 2—2 of Fig. 1; and

Fig. 3 is a section on the line 3—3 of Fig. 2.

Referring to the drawing, 1 indicates one of the end frames of that portion of a printing press which supports the inking mechanism, and 2 indicates the printing cylinder. The ink fountain is indicated at 3, and the fountain roll at 4. The usual ink distributing rolls, not shown, are arranged between the ductor roll 5 and the printing cylinder. A rocking guide frame 6 is pivoted near one end upon a stud 7, which projects from the press frame 1 below the fountain roll, and

this rocking frame is oscillated about the stud as an axis each time the printing cylinder makes one revolution. The rocking means comprises an eccentric 8, mounted on the shaft of the printing cylinder and surrounded by an eccentric strap 9, from which projects an arm 10, which is pivotally connected at 11 to the free end of the guide frame 6. The guide frame extends laterally from its pivotal point and has a longitudinal slot or guideway 12, in which is arranged a traveling nut 13, which is mounted upon a threaded adjusting bar 14, the latter extending longitudinally through the slot or guideway 12 and being suitably journaled in the ends of the guide frame. The bar 14 is provided at its outer end with a hand crank 15, by which the bar may be turned to adjust the traveling nut to different positions in the guideway. A link 16 is pivotally connected at one end to the nut 13, and at its opposite end to a bolt 17, on the driving member *a* of a friction intermittent grip device, this member being journaled upon the sleeve 18 of a driven member *b*, said sleeve being secured to the shaft 19 of the fountain roll. The member *a* comprises a disk having an annular flange 20, which surrounds several dogs 21, which are pivoted to the sleeve 18 and engage the inner surface of the flange 20. These dogs are in the form of short bars, arranged within an annular guide groove 22 in the sleeve and mounted upon pins 23, which extend through the walls of the guide groove. These bars extend outwardly in a direction which is nearly although not quite radial to the axis of the shaft 19, and the ends of the bars are kept in constant contact with the inner surface of the flange 20 by springs 24, attached to the free ends of the bars and to pins 25 which project from the sleeve 18.

It will be evident that as the printing cylinder 2 revolves, the eccentric 8 and arm 10 will cause the guide frame 6 to rock back and forth about the pivot 7, and that if the adjusting nut 13 is set close to the axis of the frame, the driving member *a* will be given little or no movement. By turning the crank 15, the traveling nut can be set at the forward end of the frame and the driving member

will be given its maximum oscillation. The upward movement of the link 16 will cause the driving member of the intermittent grip device to slip past the dogs 21, and on the 5 downward movement of the link the dogs will bind against the inner surface of the driving member and the driven member and fountain roll will be turned to a degree which depends upon the adjustment of the traveling nut in 10 the rocking guide. With the mechanism described, adjustment of the feed movements of the fountain roll may be made quickly and while the printing press is in operation and the range of adjustments is practically unlimited.

15 For the purpose of illustration, I have shown the apparatus arranged to oscillate the rocking frame and move the fountain roll once during each revolution of the printing cylinder; but in some instances this ratio is 20 changed by suitable gearing, so that the frame will be caused to oscillate once during several revolutions of the printing cylinder.

25 What I claim is:

1. In a printing press, a fountain roll, an intermittent friction grip device on the shaft of said roll, a rocking frame pivoted to the press frame below said roll, means for oscillating said frame in timed relation to the 30 movements of the printing cylinder, a threaded bar journaled in the rocking frame and extending laterally from the pivotal point of the frame, a nut threaded on to said bar, and a link pivoted to said nut and to the driving member of said intermittent grip device.

35 2. In a printing press, a fountain roll, an intermittent friction grip device on the shaft of said roll, a rocking frame pivoted to the press frame below said roll, means for oscillating said frame in timed relation to the 40 movements of the printing cylinder comprising an eccentric operated by the shaft of said cylinder and an arm movable by the eccentric and pivotally connected to the rocking frame, a threaded bar journaled in the rocking frame and extending laterally from the pivotal point of the frame, a nut threaded on to 45 said bar, and a link pivoted to said nut and to the driving member of said intermittent 50 grip device.

In testimony whereof I affix my signature.
HENRY B. GREENWOOD.
